Patented May 9, 1922.

UNITED STATES PATENT OFFICE.

ALBERT D. SMITH, OF DETROIT, MICHIGAN.

ROTARY TAKE-UP FOR SEWING MACHINES.

1,415,269.

Specification of Letters Patent.

Patented May 9, 1922.

Application filed August 20, 1918. Serial No. 250,651.

To all whom it may concern:

Be it known that I, ALBERT D. SMITH, a citizen of the United States, residing at Detroit, in the county of Wayne and State of Michigan, have invented certain new and useful Improvements in Rotary Take-Ups for Sewing Machines, of which the following is a specification.

This invention relates in general to sewing machines, and the primary object is to provide a rotary take-up of simplified and generally improved construction with the view to accomplishing certain desired results.

For example, it has heretofore been necessary in the use of rotary take-ups to provide special mechanism for regulating the amount or length of thread given down at each stitch in accordance with the thickness of the goods. It has also been necessary to provide special devices, spring-actuated controllers, differential driving mechanism, etc., for controlling the slack thread in the take-up at certain times in the operation. These special devices not only complicated a sewing machine and increased the cost of production, but very frequently were so impractical as to cause the thread to become wound in the take-up and broken. It is to overcome these deficiencies that my present rotary take-up has been designed.

One of the features of my present invention is the provision of an improved take-up which enables goods of any thickness to be sewed without the provision of special devices for varying the length of thread given down for the different thicknesses of goods. At the same time, perfect stitches are obtained under all circumstances.

Other objects and attendant advantages will be appreciated as the invention becomes better understood by reference to the following description when considered in connection with the accompanying drawings, in which—

Figure 1 is an end elevation of a sewing machine head having a rotary take-up embodying my improvements;

Figs. 2 and 3, vertical sectional views taken substantially on the lines 2—2 and 3—3, respectively, of Fig. 1;

Figs. 4 and 5 horizontal sectional views taken substantially on the lines 4—4 and 5—5, respectively, of Fig. 1;

Fig. 6, a side view looking at the left hand side of Fig. 1; and

Fig. 7, a development of the annular wall that circumscribes the take-up disks.

My present improvement is illustrated in connection with a sewing machine of the rotary hook type, and the parts not necessary for an understanding of the invention have been omitted. The well known parts comprise the work table 9, rotary hook 11, machine head 12, needle bar 13, presser bar 14 and the lever 15 for lifting the presser bar.

On the end of the machine head 12, I have secured in a suitable manner, a cover plate designated generally by character 16, shaped to provide a casing 17 for the rotary take-up disks 18 and 19. This casing is provided with a peripheral wall or flange of novel shape to provide certain thread-guiding surfaces, the purpose of which will presently appear.

The take-up proper consists of the disks 18 and 19 connected together by but a single eccentric thread-engaging means or pin 21, preferably of relatively large diameter. These disks are positioned in comparatively close relation as shown, and the inner disk 18 is fixed to a hub 22 adapted to be secured to the needle-bar driving shaft or an extension thereof, so that the take-up disks are rotated directly with said driving shaft. In the present case, the rotary hook 11 is revolved three times to each revolution of the take-up, and when the needle is at its highest point the rotary hook and the take-up are in the relative relation shown in Fig. 1.

Just beneath the rotary take-up, I have positioned on the plate 16 a pair of thread-guiding staples 23 and 24, the former of which guides the thread as it enters between the take-up disks and the latter as it leaves the disks. The thread guides are positioned in certain relation to and co-operate with the thread-guiding surfaces formed by the annular wall or flange of the casing 17, the shape and purpose of which surfaces will now be described.

As clearly shown in the drawings, the annular casing wall designated generally by character 25, is formed at its lowermost point in the perpendicular plane of the needle with a cutaway providing what may be termed a low surface 26 substantially flush

with the outer surface of the disk 18. The take-up revolves in a clockwise direction; and as shown clearly in Figs. 3 to 6 inclusive, that portion of the wall 25 at the intake 5 side of the take-up gradually increases in depth from the point 26 to a high point 27, providing a gradually inclined thread-guiding surface 28 which crosses obliquely the space between the rotary disks. As shown in 10 Fig. 6, the wall 27 decreases in height as it approaches the uppermost point 29 of the casing, although this is not essential to the operation, and the purpose is simply to give access to the space between the disks at this 15 point. Viewing Figs. 2, 6 and 7, it will be noted that the wall at the descending side of the take-up gradually increases in depth and terminates in an abrupt shoulder 31 at the lowermost point in the take-up. It will 20 be further noted that the portion 32 of the wall extends a substantial distance beyond the outermost disk and also beyond the thread guide 24. The function of this wall portion 32 is very important, since by its 25 use I am enabled to dispense with various auxiliary devices which have been heretofore necessary for controlling the slack thread and also for regulating the amount of thread given down for sewing goods of different 30 thickness. Regarding the thread-guiding staple 24, it will be noted that this staple is so positioned as to hold the outgoing thread in line with the needle and to also impose a slight tension on this thread so as 35 to prevent the thread from falling freely from between the take-up disks. The purpose of imposing this slight tension on the outgoing thread at this point will be more readily apparent after a consideration of the 40 complete operation.

The present take-up is designed to produce a relatively large slack of thread necessary to be passed around an unusually large lower thread receptacle of the character described 45 in my co-pending application, Serial No. 247,423, filed July 30, 1918, and because of the relative timing of the rotary hook and take-up necessitated by revolving these parts at a uniform speed as distinguished 50 from a differential speed, a large slack of thread is momentarily produced in the take-up. This slack of thread must be properly controlled at this instant, otherwise the thread will invariably cause the rotary hook to foul or will become wound in the take-up or caught on some stationary part, thereby resulting in breaking of the thread. Such an occurrence is prevented by reason of the 55 peculiarly shaped wall portion or pocket 32 at the lower descending side of the take-up and by the manner in which the thread leaves the take-up under the influence of a slight tension imposed by the staple 24. As shown in Fig. 1, the upper spool thread is 60 passed beneath the staple 23, and guided

along the surface 28, it enters beneath the outermost disk 19 and passes over the eccentric stud 21, it being noted that there is sufficient clearance between the periphery of the disk 19 and the internal surface of the 70 wall 25 to permit passage of the thread between this disk and entirely around the take-up in a clockwise direction until the point 26 is reached, whereupon the thread is passed beneath the staple 24, which is disposed almost entirely beneath the pocket portion 32 of the thread-controlling wall. The thread now leaves the take-up directly above the needle at all times. When the take-up pin 75 21 reaches approximately the point A, Fig. 80 1, there is a maximum of slack loose thread between the disks which loose thread, due to centrifugal force, is thrown outwardly and strikes the wall 32. This wall as shown, extends a substantial distance 85 outwardly from the outermost disk and constitutes a pocket or controller for preventing the thread from being caught on any projection, such for example as the staple 24. At the same time, the tension imposed by the 90 outgoing thread passing over the edge 31 and beneath the staple 24 prevents this slack thread from falling from the take-up and interfering with the control of the thread between the take-up and the rotary hook. 95

By reason of the foregoing construction, it is not necessary to provide auxiliary means for varying the amount of thread given down when sewing goods of different thickness. As a result, perfect stitches are obtained 100 without adjustment of any kind, regardless of the thickness of the goods. The take-up is so proportioned and timed that the thread is just taut when the needle enters the finest goods. From this instant, the take-up pin 105 descends at the rate of about 14 times the speed of the needle and produces the proper amount of slack for the heavy goods. Thus no auxiliary means is necessary to vary the amount of slack given down when goods of 110 different thickness are sewed, because in the present instance the surplus slack when sewing thin goods is fully controlled and sufficient amount of slack is produced at all times to sew goods of any thickness. 115

It is believed that the foregoing conveys a clear understanding of my improvement, and it should be understood that while I have illustrated and described a single working embodiment thereof, changes might be made 120 in the proportions and arrangement of parts without departing from the spirit and scope of the invention as expressed in the appended claims.

I claim:

1. A rotary take-up structure for sewing machines comprising a pair of rotary disks connected by an eccentric thread-engaging means, thread guides at the underside of the take-up as it enters between and leaves the 130

- disks so that a comparatively large slack of thread is produced, and means for controlling the slack thread when the eccentric thread-engaging means descends, comprising 5 a casing for the rotary disks open at the front thereof and having an annular wall at the descending side of the disks extending outwardly a substantial distance beyond the outermost disk.
- 10 2. In a sewing machine, the combination with the head, of an end plate on the head having an annular outstanding flange, a pair of revoluble disks disposed within said annular flange and connected together by but a 15 single eccentric thread engaging means, the lower flange portion at the descending side of the take-up disks being extended outwardly a substantial distance beyond the outer disk and cut away substantially in the 20 perpendicular plane of the needle and directly below the space between the disks, the flange being further cut away on its opposite lower portion to provide an outer surface ex-
- tending at a gradual inclination outwardly and upwardly from below said space between 25 the disks, and thread guiding means for guiding the thread to pass over said second cut-away to enter between the disks and to leave the disks through said first cutaway.
3. In a sewing machine, the combination 30 of a pair of rotary take-up disks, thread take-up means interposed between the disks leaving a substantially uninterrupted thread compartment therebetween, thread-guiding means for causing the thread to enter and 35 leave said compartment from the underside of the disks, and a wall circumferentially about and in close proximity to the periphery of the disks constituting an outer wall to said compartment and shaped at the lower descending side of the take-up to extend substantially beyond the outer disk for controlling the slack thread substantially as described.

ALBERT D. SMITH.
